[57] **CLAIM**

The ornamental design for a soap dish, as shown and described.

DESCRIPTION

FIG. 1 is a top, front, and right side perspective view of a soap dish showing my new design;

FIG. 2 is a top plan view thereof;

FIG. 3 is a vertical cross-sectional view thereof, taken along line 3—3 of FIG. 2;

FIG. 4 is a vertical cross-sectional view thereof, taken along line 4—4 of FIG. 2;

FIG. 5 is a bottom, rear, and left side perspective view thereof, showing the soap dish flipped over in an alternate position, and,

FIG. 6 is a bottom plan view thereof.

FIG.1

FIG.4
